UNITED STATES PATENT OFFICE.

NED E. BARNES, OF WILLIS, TEXAS.

TIE PLATE AND JOINT BRACE.

Application filed March 7, 1927. Serial No. 173,483.

This invention relates to new and useful improvements in a tie plate and joint brace.

One object of the invention is to provide a device of the character described, designed to rest on a railway tie underneath the joint formed by the abutting ends of the adjacent rails, and formed with a wing plate adapted to conform to the contour of and fit against the outer side of the rails to hold said ends of the rails in alignment and to prevent the spreading of the rails.

Another object of the invention is to provide a device of the character described, which is of simple structure and can be cheaply produced, readily applied and which is very efficient in use.

With the above and other objects in view this invention has particular relation to certain novel features of construction, arrangement of parts and use, an example of which is given in this specification and illustrated in the accompanying drawings, wherein:

Figure 1 shows a plan view of a section 25 of a railway track with the tie plate applied to the joint thereof.

Figure 2 shows a side elevation thereof.

Figure 3 shows a transverse sectional view taken on the line 3—3 of Figure 2, and

Figure 4 shows a transverse sectional view taken on the line 4—4 of Figure 2.

Referring now more particularly to the drawings, wherein like numerals of reference designate similar parts in each of the drawings, the numeral 1 designates the ties of a railway track and the numerals 2, 2, designate adjacent rails whose ends abut to form a joint over one of said ties. Underneath said joint, on the rail there is a plate 3 whose underside is provided with suitable teeth, as 4, to bite into the tie underneath to prevent slippage of said plate. Spikes, as 5, are driven through suitable openings in the plate, adjacent the inside and outside edges of the base, or foot, of the rail and into the tie beneath with the head engaging over said edges to hold the plate 3, as well as the rail, on the tie.

There is a wing plate 6 which conforms to 50 the contour of and fits against the outer side of the rail web and overlies the adjacent base of the rail, and is disposed to break the joint between the abutting ends of adjacent rails. This wing plate is joined with the tie

plate 3 by means of a central leg 7 which 55 fits closely over the adjacent base of the rail and is integrally formed with the plates 3 and 6. There is the usual fish plate 8 which conforms to the contour of and fits against the inside of the rail opposite the 60 wing plate 6, said opposing plates being substantially equal in length, and being securely clamped against the respective sides of the rail by means of the clamp bolts 9. The plates 6 and 8 extend each way beyond 65 the joint a sufficient distance to give the required strength and overlap, not only the tie underneath the joint but the adjacent ties on each side and thus prevent not only the 70 sinking of the rails at the joints but also the spreading of the rails.

The wing-plate 6 may be reinforced, if desired, by means of the web 6' formed integrally therewith and extending transversely with respect to said plate. 75

What I claim is:

1. A tie plate and joint brace including an elongated base plate adapted to rest on the railway ties underneath abutting ends of the railway rails, a wing plate which conforms to the contour of and is adapted to fit against the outer side of the rail web and which is adapted to overlie the adjacent base of the rail and is disposed to bridge the joint between the abutting ends of adjacent rails, a central leg adapted to fit closely over the adjacent base of the rail and which is formed integrally with the base plate and wing plate, a fish plate adapted to conform to the contour of and fit against the inside of the rail and disposed opposite said wing plate, said fish plate and wing plate being substantially equal in length and being extended each way beyond the joint a sufficient distance to overlie not only the tie underneath the joint but the adjacent ties on each side and a web formed integrally with said leg and said wing plate extending transversely of the latter. 90

2. A tie plate and joint brace including an elongated base plate adapted to rest on the railway ties underneath abutting ends of the railway rails, a wing plate which conforms to the contour of and is adapted to fit against the outer side of the rail web and which is adapted to overlie the adjacent base of the rail and is disposed to bridge the joint between the abutting ends of adjacent rails, 100

a central leg adapted to fit closely over the adjacent base of the rail and which is formed integrally with the base plate and wing plate, a fish plate adapted to conform to the contour of and fit against the inside of the rail and disposed opposite said wing plate, said fish plate and wing plate being substantially equal in length and being extended each way beyond the joint a sufficient distance to overlie not only the tie underneath the joint but the adjacent ties on each side. In testimony whereof I have signed my name to this specification.

NED E. BARNES.
